UNITED STATES PATENT OFFICE.

AMES J. HOLLAND, OF PHILADELPHIA, PENNSYLVANIA, AND WILLIAM DISCHER,
OF TOLEDO, OHIO.

COMBINATION ATOMIZER AND NEBULIZER.

1,020,647.

Specification of Letters Patent. Patented Mar. 19, 1912.

Application filed May 11, 1911. Serial No. 628,473.

To all whom it may concern:

Be it known that we, JAMES J. HOLLAND and WILLIAM DISCHER, citizens of the United States, residing at Philadelphia, in the county of Philadelphia and State of Pennsylvania, and Toledo, in the county of Lucas and State of Ohio, respectively, have invented certain new and useful Improvements in Combination Atomizers and Nebulizers, of which the following is a specification.

This invention is a combination atomizer and nebulizer for spraying and vaporizing various liquids, and also provides for a combined nasal dilator and throat spray, or the like.

The object of this invention is to provide such a device which is hygienic in use, having means for arresting any nasal or other excretions containing bacteria or germs which tend to flow back into the container, thus preventing the infection of the liquid therein.

Another object is to provide means for readily converting the device for use either as an atomizer for spraying, or as a nebulizer for vaporizing oily and other solutions.

It is well known in the art that a spray is created by the action of a current or jet of air over the end of a tube which communicates with the liquid to be sprayed, causing a mixture of air and small particles or drops of the liquid, while a nebulizer is an additional step in which the spray is caused to assume a vaporous state by being muffled or arrested from direct emission, such as being caused to strike a wall prior to its emission. Both are in common use, the spray being used to coat a surface with the liquid and a nebulizer being used to form a vapor to be received by the respiratory organs for medical purposes. It is also known that all liquids can be sprayed, while only certain liquids can be vaporized as above indicated without heat being employed. Oily solutions can readily be vaporized as above indicated, while aqua solutions require the action of heat to attain a vaporous state.

To the above end this invention is embodied in a novel combination and arrangement of parts, as will be hereinafter described, and as is shown in the accompanying drawings, in which similar reference

characters indicate similar parts, and in which—

Figure 1 is a perspective of the device as used as a throat spray, or the like, being arranged as an atomizer, and Fig. 2 is a vertical section thereof, part broken away, arranged as a nebulizer for creating a vapor for nasal dilation, or the like.

Referring specifically to the drawings, the container is shown at 3, having the upper sleeve 9 into which screws the head 8. Through the said head 8 pass the concentric tubes 4 and 5, the outer tube 4 terminating at its lower end, about midway in the container, and the inner tube 5 extending to the bottom of the container. At their upper and outer ends the said tubes have a portion thereof bent angularly for convenience in use. A nipple 7 projects from the head 8, and has the duct thereof in communication with the chamber or passage between the tubes 4 and 5. To the nipple 7 is connected a bulb 6, or any other means, for creating a flow of air.

The outer end of the tube 4 has an internal thread into which screws a tip 10 having a rear recess or bore 13, and a small aperture or outlet hole 11 passes out the front end of the said tip from the said recess. The said recess is of larger diameter than the inner tube 5 and the said tube projects therein to a point directly back of the aperture 11. Externally the tip 10 has the same contour as the tube 4 with the exception that it tapers outwardly toward its outer end.

A muffling hood or dilating tip 15 is slidably arranged on the outer end of the tube 4 by means of the bore 12 therein through which the said tube passes. At the front end of the hood is a counter-bore 16 of larger diameter than the tip 10, and the front end of the said hood is spun inwardly to form an annular lip 17, thus partially closing the opening of the said hood. The hood upon being slid forward over the tip 10 is held in such position by the tapered face of the tip binding in the bore 12 thereof. This also prevents the removal of the said hood unless the tip 10 is unscrewed from the tube 4. The counter-bore or recess 16, when the hood is pulled forward, extends back of the for-

ward end of the tip 10 to provide a chamber or trap 14 back of the aperture 11.

In use, air is forced into the air chamber or passage between the tubes 4 and 5 forming a compression in the bottle or container 3 as the lower end of the said passage is in communication with the space above the liquid in the container, and the air is forced to escape out the aperture 11 around the outer end of the inner tube 5 which communicates with the liquid in the container, thus causing the liquid to rise in the tube 5 and emit out the outer end thereof to mix with the escaping air to form a spray. With the compression type as here described a continuous spray is created, this also affording a continuous vapor to be created when the device is used as a nebulizer which is of great advantage over the present nebulizers which create an intermittent vaporous emission due to the bulb action. Thus, when the hood or dilating tip 15 is drawn back the device acts as the ordinary compression spray, but when the hood 15 is drawn forward over the tip 10 the spray is muffled by the lip 17 and a vapor is created, causing the action of a nebulizer, and the hood or tip 15 adapting the device for dilatory purposes. It will also be seen that any nasal excretions or other foreign matter within the hood will be taken up by the chamber or trap 14 and thus be arrested from entering the container. Such matter which accumulates in the said trap 14 can be readily emptied whenever desired.

It will be seen that the objects aimed at are attained in an efficient and convenient manner, and it is desired to allow for alterations of the device within the scope of the appended claims, and not to limit same to the

specific form as herein described and as shown in the drawings.

Having described our invention, we claim as new:

1. In a device of the character described, the combination of a container, concentric tubes passing out thereof, a spray tip on the outer ends thereof having a forward outlet aperture, and a muffling tip having a bore therethrough through which the outer tube passes and a forward counter-bore of larger diameter than the said spray tip, the forward end of said muffling tip having an inwardly projecting lip partially closing the opening therein formed by the said counter-bore and the said muffling tip being slidable on the said outer tube to slide over the spray tip and away therefrom.

2. In a device of the character described, the combination of a container, concentric tubes passing out thereof, a spray tip on the outer ends thereof having a forward outlet aperture, and having an outward taper and a muffling tip having a bore therethrough through which the outer tube passes and a forward counter-bore of larger diameter than the said spray tip, the forward end of said muffling tip having an inwardly projecting lip partially closing the opening therein formed by the said counter-bore and the said muffling tip being slidable on the said outer tube to slide over the spray tip and away therefrom.

In testimony whereof we hereunto affix our signatures in presence of two witnesses.

JAMES J. HOLLAND.
WILLIAM DISCHER.
